UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

INKSTAND.

1,389,650.

Specification of Letters Patent. Patented Sept. 6, 1921.

Application filed March 25, 1920. Serial No. 368,805.

To all whom it may concern:

Be it known that I, FRANZ A. FULLER, a citizen of the United States, residing in the city of Newark, in the county of Essex and State of New Jersey, have invented certain new and useful Improvements in Inkstands, of which the following is a full, clear, and exact description, such as will enable others skilled in the art to which it pertains to make, construct, and use the same, reference being had to the accompanying drawings and to numerals of reference marked thereon, forming a part of this specification.

This invention has for its object to provide an ink stand adapted for the reception of an ink well or the like, which shall be simple and effective in construction, and comparatively inexpensive in cost.

My improved stand is of such form that it is well adapted for advertising purposes, in that the advertisements may be placed or embossed in any suitable manner upon the sides thereof.

With this end in view, my invention consists in certain novelties of construction and arrangements of parts, as hereinafter set forth and pointed out in the claims.

While the preferred form is illustrated in the accompanying drawings, yet it is to be understood that minor changes may be made without departing from the scope thereof.

In the accompanying drawings,

Figure 1 represents, a plan view of my improved stand in its closed position.

Fig. 2 represents, a longitudinal section taken on line 2—2 of Fig. 1 looking in the direction indicated by the arrows.

Fig. 3 represents, an under plan view taken on line 3—3 of Fig. 2 looking in the direction indicated by the arrows, the base plate being removed and shown in dotted lines in said figure.

Fig. 4 represents, a transverse section of the stand taken on line 4—4 of Fig. 1 looking in the direction indicated by the arrows, showing the lid in open dotted position.

Fig. 5 represents, a side elevation of the tubular bearing and the end pins by means of which the lid is hingedly secured to the stand.

Fig. 6 represents, the blank from which the bearing is made.

Fig. 7 represents, an enlarged sectional view taken on line 7—7 of Fig. 4 looking in the direction indicated by the arrows; and

Fig. 8 represents, a similar view taken on line 8—8 of Fig. 1 looking in the direction indicated by the arrow.

Similar numerals of reference refer to like parts throughout the specification and drawings.

The improved stand is preferably made of flexible sheet metal of any kind, such as brass, tin, copper or aluminum, and the parts are of such shape as to lend themselves readily to manufacture by the use of suitable punches and dies from ordinary sheet metal.

My improved stand consists essentially of the base plate 10, the two side plates 11, the central cover plate 12, and the lid 13, said lid being pivotally secured to the cover plate 12 in any convenient or desired manner, preferably by means of the tubular bearing 14 and the pins 15.

The base 10, in its preferred form, is preferably rectangular in shape, provided with curved sides 16, said sides terminating in an outwardly extending marginal flange 17, thereby imparting to said plate the desired degree of rigidity and stability.

Located in close proximity to the longitudinal sides 16 of the base plate 10, are a plurality of apertures 18 preferably three on each side, the purpose of which will be hereinafter described.

Each of the side plates 11 is provided with an inwardly extending flange 19, extending along the upper and side edges thereof, designed to overlap the central cover plate 12, and engage with the depressed portion 20 extending along the entire edge of said cover plate 12, as more clearly illustrated in Fig. 7 of the drawings.

The lower edge of each of the side plates 11, is provided with a plurality of downwardly extending lugs 21, designed to pass through the apertures 18 in the base plate 10, and which are clenched over on the under side of said base plate as clearly indicated in the drawings.

The inwardly extending flange 19 of the side plates 11, is also provided with similarly arranged lugs 22 there being one lug on each end flange, and two lugs on the top

flange, the purpose of which will be hereinafter described.

The central cover plate 12, which is provided with upwardly and inwardly extending curved sides 23, as heretofore stated, is provided along its two longitudinal edges with a depressed portion 20 to receive the inwardly extending flanges 19 of the side plates 11, and adjacent to said depressed portion with a downwardly extending flange 36 extending along the entire longitudinal edge of said plate. This flange when the parts are in an assembled position abuts against the inner marginal portions of the side plates, thereby imparting to the assembled structure great rigidity.

Each depressed portion 20 of the cover plate 12 is provided with a corresponding number of apertures 24 to receive the lugs 22 of the side plates 11, which are designed to be clenched over on the under side of said cover plate 12.

The central portion of the cover plate 12 is provided with a downwardly and inwardly arranged apertured seat 25, for the reception of an ink well 26, shown in dotted lines in Figs. 1 and 2 of the drawings.

The cover plate 12, as clearly indicated in Fig. 3 of the drawings, is further provided with two apertures 27 designed to receive the lugs 28 projecting from the tubular bearing 14 and by means of which, said tubular bearing 14 is rigidly secured to the top of the cover plate by clenching said lugs over on the under side of said cover plate, as clearly indicated in Figs. 3 and 8 of the drawings.

The lid 13, is of a box like structure and along its front edge is provided with a finger piece 29 by means of which the same may be manipulated.

The rear wall of the lid 13, is provided with two apertured lugs 30 through which the pins 15 pass, and which are received into the tubular bearing thereby pivotally securing said lid to the top of the cover plate 12.

The rear wall of the lid 13, see Fig. 4 of the drawings, is slightly cut-away as at 31 so as to permit said wall to contact with the top of the side plate 11, as clearly indicated in dotted lines in Fig. 4 of the drawings, thereby providing a stop to limit the rearward movement of said lid.

In assembling my improved ink stand, I first secure the two side plates 11 to the cover plate 12, by snapping the four lugs 22 of the side plate into the four apertures 24 arranged in the depressed portion 20 of the cover plate 12, and thereafter bending the lugs 22 against the underside of the depressed portion 20 of the cover plate 12.

The tubular bearing 14 is then secured to the cover plate by snapping the lugs 28 into the apertures 27 of the cover plate and thereafter bending the lugs against the under side 65 of the cover plate.

The lid 13 is then hingedly secured to the bearing 14 by inserting the pins 15 through the apertured lugs 30 of the lid and forcing the pins into the tubular bearing until the heads 32 of the pins engage with the outside 70 of said lugs.

The stand, as now assembled, is now held in position on the base plate by the lugs 21 of the side pieces 11 through the apertures 18 of the base plate and bending them over 75 at right angles against the under side of the base plate 10.

It will thus be seen that I have dispensed with the use of solder, rivets, bolts or the like, and employ suitable lugs or ears and apertures for rigidly securing the parts together, thereby facilitating the assembling 80 of the device, and reducing the cost thereof to a minimum.

Experience has demonstrated that the organization above described is a highly efficient one, and while the device described is the preferred embodiment of my present invention, I do not care to restrict myself to the exact details of construction, combination and arrangement of parts herein set forth, it being obvious that minor variations thereof, not involving the exercise of invention, may be made by any skilled mechanic, and such departures from what is herein described and claimed, I consider within the scope and terms of my claims.

Having thus described my invention, what I desire to claim and secure by Letters Patent is:—

1. An inkstand comprising a sheet-metal base plate, a sheet-metal cover plate provided with marginal depressed portions mounted upon said base plate, sheet-metal side plates provided with marginal flanges 90 105 to engage said depressed portions secured to the longitudinal edges of the cover plate, said side plates each being provided with marginal integral interlocking means for securing the cover plate and side plates to 110 the base plate.

2. An inkstand comprising a sheet-metal base plate, a sheet-metal cover plate provided with a centrally-arranged depressed portion mounted upon said base plate, sheet-metal 115 side plates secured to the longitudinal edges of the cover plate, said side plates each being provided with marginal integral interlocking means for securing the cover plate and side plates to the base plate, and a sheet-metal lid provided with a cut-away portion to limit its upward movement hingedly secured to the cover plate.

3. An inkstand comprising a sheet-metal base plate, a sheet-metal cover plate provided with a centrally arranged depressed portion mounted upon said base plate, and further provided with marginal depressed portions, sheet-metal side plates provided with marginal flanges adapted to engage 125 130

with the depressed portions of the cover plate, secured to the said cover plate, said side plates each being provided with marginal interlocking means for securing the 5 cover plate and side plates to the base plate, and a sheet-metal lid, provided with a cut-away portion to limit its upward movement hingedly secured to the cover plate.

4. An inkstand comprising a sheet-metal 10 base plate, a sheet-metal cover plate provided with a centrally-arranged depressed portion mounted upon said base plate, and further provided with marginal depressed portions, sheet-metal side plates provided with marginal flanges adapted to engage with the depressed portions of the cover plate, secured 15 to the said cover plate, said side plates each being provided with marginal interlocking means for securing the cover plate and side 20 plates to the base plate, and a sheet-metal lid provided with a cut-away portion to limit

its upward movement hingedly secured to the cover plate.

5. An inkstand comprising a sheet-metal 25 base plate, a sheet-metal cover plate provided with a centrally-arranged depressed portion mounted upon said base plate, sheet-metal side plates secured to the longitudinal edges of the cover plate, said side plates each being provided with marginal integral 30 interlocking means for securing the cover plate and side plates to the base plate, and a sheet-metal lid provided with a cut-away portion to limit its upward movement hingedly secured to the cover plate. 35

This specification signed and witnessed this 24th day of March, 1920.

FRANZ A. FULLER.
